UNITED STATES PATENT OFFICE.

PASQUALE GALASSI, OF NEW YORK, N. Y.

INSERT FOR FLOORINGS AND PAVEMENTS.

Application filed January 18, 1928. Serial No. 247,618.

This invention relates to improvements in the construction of floors of the terrazzo type and more particularly refers to a novel and improved element of floor construction, which is adapted to manifold increase the decorative possibilities of such floors, and which is also adapted to confer to said floors desirable and effective anti-slip properties.

Terrazzo, monolithic and similar floors where various combinations of design may be produced, usually comprise a foundation bed or layer of concrete, cement, marble or other suitable material and an upper or finishing layer which generally consists of a mixture of marble chips and cement, and which may be made in a number of different color combinations.

The upper layer which is placed in position while in a plastic condition, eventually hardens providing a very durable surface, capable of taking a high polish upon the completion of the finishing operations. In order to localize cracks which may occur throughout the material of which the floor is composed, the upper layer is generally divided into panels or blocks or units by means of strips laid on top of or inserted through the foundation layer, said strips having their upper edges level with the surface of the floor and affording means for producing a great variety of designs and color effect. In practice, it has been found that terrazzo floors laid in the customary manner described, are effective, durable and relatively inexpensive, but being as they are extremely smooth, they do not afford sufficient protection against slipping.

This lack of anti-slip properties is especially objectionable in public buildings, corridors, halls, etc., and still more in such places where the floor slopes down an incline. In order to prevent accidents therefore, the upper layer of the terrazzo floors used in such places is frequently made of some special composition containing among its ingredients some anti-slip material; for instance, to the ordinary mixture of marble chips and cement, may be added a certain proportion of alundum or carborundum, or quartz sand, these materials being highly effective in increasing the frictional and adhesive properties of the floor, but on the other hand, giving occurrence to some undesirable effects which are absent in terrazzo floors of ordinary construction.

For instance, anti-slip floors produced by

means of compositions of the character specified are darker in texture than those produced in the usual compositions, and do not take a good polish; furthermore, their cost is considerably higher, both because the cost of the material itself is higher and because the laying and finishing operations required entail the expenditure of considerable more time and labor.

Another objection which may be raised in connection with these floors, is that they easily and quickly collect dirt and dust, which can be removed only in part and with difficulty; from a sanitary standpoint therefore, these floors are inferior to terrazzo floors of the ordinary type.

Terrazzo floors generally are furthermore subject to certain limitations which are incident to the nature of the strips which are used in outlining their design so as to divide the floor into a number of units or panels. These strips have frequently sufficient flexibility to permit their being bent around to form geometrical figures such as a circle, or square, or oval, etc., but here their possibilities from a decorative standpoint end.

By means of these strips it is possible to obtain a great number of pleasing combinations where the panels formed in the floor are in all cases separated by continuous lengths of strips of a uniform thickness. Only elementary designs can therefore be thus produced, and highly ornamented designs displaying more elaborate metallic outline effects are impractical or impossible to obtain.

The primary object of this invention is to provide a novel type of element for the construction of terrazzo and similar floors, in the nature of an insert or centerpiece or rosette or other unit of decorative nature, providing individual designs in unit form, which can be embedded in the floor material, so as to have their upper decorative edges level with the surface of the floor.

In terrazzo floors proper, these units should preferably be used in conjunction with the ordinary dividing strips, because the necessity of dividing the floor surface into panels or units still remains; but in such floors where a monolithic construction may be used, the inserts can also be used by themselves providing the only motive of decoration, or else they may also be used in conjunction with the strips as parts of the general decorative scheme.

Another object of this invention is to pro-

vide decorative units of the character specified, adapted for use in connection with floors of the terrazzo type, said units being provided with means for joining or combining them 5 with dividing strips in order to produce various decorative schemes and combinations.

A further object is to provide unitary decorative elements of the character specified, which besides being adapted to produce novel 10 and numerous designs and decorative effects, shall also be adapted to produce an anti-slip floor surface, such units being made with or being adapted to receive and retain anti-slip material the upper surface of which will be 15 flush with the remaining surface of the floor.

A still further object is to provide decorative units of the character specified, adapted for use in floors made of originally plastic material and adapted by virtue of their construction to supplement or to entirely substitute the ornamental action now obtained by means of dividing strips; said decorative units being furthermore adapted to generate designs and decorative schemes which are entirely beyond the range of the possibilities afforded by dividing strips and similar materials. 25

Other objects and advantages of the present invention will more fully appear as the 30 description proceeds and will be set forth and claimed in the appended claims.

Decorative floor units embodying my invention may be produced in practically unlimited variety of designs, and sizes; and for 35 a better understanding of my invention, in the annexed drawings I have shown a few representative types of units embodying my invention.

Referring to said drawings:

40 Fig. 1 is a fragmentary plan view of a floor, the decorative motive of which is obtained entirely by means of rosettes or center pieces, embodying my invention;

45 Fig. 2 is a fragmentary plan view of a floor illustrating a combined effect of dividing strips and center pieces;

Fig. 3 is a similar view illustrating a different design;

50 Fig. 4 is a fragmentary plan view of a floor, formed entirely by square units adjoining one another;

Fig. 5 is a fragmentary plan view of another floor, the decorative effect of which is obtained by means of spaced square units;

55 Fig. 6 is a plan view in an enlarged scale of a unit or rosette of the type illustrated in Fig. 1;

Fig. 7 is a side view in elevation, partly broken away and sectioned of the same;

60 Fig. 8 is a plan view of still another type of rosette or center piece;

Fig. 9 is a sectional view in elevation thereof;

Fig. 10 is a plan view of a square unit or 65 insert; and

Fig. 11 is a cross sectional elevation of the same through line 11—11 of Fig. 10, illustrating the manner of placing the unit or insert in position.

From the drawings, Figs. 1 to 5, it may be seen that my novel and improved floor insert affords means for producing a practically unlimited variety of designs, which cannot be obtained by means of the dividing strips now used; and in so far as the ornamental features are concerned, it is, of course, immaterial whether the inserts are of anti-slip nature or not. 70 75

Thus in Fig. 1, a pleasing design is obtained by arranged annular inserts 20 in parallel rows in staggered relation to one another; and in Fig. 2 another design is obtained by means of ordinary strips 21, 22, disposed cross wise, so as to form a checkered design, and round inserts 23 arranged in the center of each square panel. 80

The design illustrated in Fig. 3 on the other hand, consists of parallel rows of round inserts 24, connected to one another by short lengths of dividing strips 25. 90

Fig. 4 illustrates a different type of insert 26, having a square outline and adapted therefore to be laid tile fashion so as to entirely cover the surface of the floor. The same type of insert is illustrated in Fig. 5 95 where said inserts 27 are spaced from each other and arranged in parallel rows.

The inserts may be made in any suitable or desired outline and are in the nature of skeleton open frames having vertically projecting 100 rib members forming the desired design; in this manner, they may be fully embedded and retained in the material of which the floor is composed, the binding action taking place between the material and the inserts being similar to that now taking place between the material and the dividing strips. 105

In other words, the main body of the floor itself is still composed mainly of granolithic or marble composition; but the designs are obtained by means of rosettes or inserts forming the object of the present invention or by combinations or rosettes or inserts and dividing strips. 110

My invention may be carried into practice 115 as stated, by means of rosettes or inserts having plain edges, or else for special purposes, rosettes or inserts having anti-slip outlines may be produced.

In Figs. 6 to 11, of the drawings, I illustrate several types of rosettes or inserts adapted for the production of anti-slip floors. For instance, the rosette illustrated in Fig. 6 is composed of two concentric rings 29, 30, each formed with an open top dovetailed chamber 31, 32, which may be filled with lead or other suitable anti-slip material 33 as shown. The two rings are joined by a horizontal perforated rib 34 from which depends a circular rim 35 having a suitable depth. 120 125 130

The lower portion of said rim is preferably notched as shown at 36, in order not to destroy the continuity of the material through which the rim is inserted, at the same time 5 providing better anchoring properties. The rim portion 35 is preferably provided with flange segments such as 37, laterally projecting therefrom, limiting the depth at which the rim member is to be forced through the 10 foundation layer of the floor.

The lower surface of these flangs is preferably at a distance from the upper surface of the rings, equivalent to the depth of the finishing layer of the floor, so that when the inserts 15 are set in position, they act as a gauge for determining the thickness of the finishing layer. At the same time the flanges 37 also act as anchoring means binding the rosettes or inserts to the floor material.

20 If desired, a single circular flange extending throughout the entire circumference of the insert may be provided, but I prefer to use flanges of a segmental nature as shown, because it is thus possible to separate adjoining flanges by means of slots such as 38 providing housings through which the free ends of dividing strips such as 39 may be inserted.

Neither the flange or flanges, nor the strip housings show through when the rosette or 30 insert is placed in position, so that a rosette of this character may be used both for producing floors of the types illustrated in Figs. 1 and 2, or for producing floors of the type illustrated in Fig. 3.

35 In Figs. 8 and 9, I illustrate another type of anti-slip circular rosette, having the outline of a spoked wheel, the same comprising an annular head member 40 formed integral with radial members 41, joined at the center 40 to form the hub of the wheel.

The entire structure described is formed with an open top dovetailed chamber 42, which may be filled with anti-slip metal or composition 43, as shown.

45 The annular head is provided with a depending rim member 44, the lower portion of which is preferably dented or notched as shown at 45 for the reasons stated before. Furthermore, said rim member is also provided with spaced laterally extending lugs or flange members 46, 47, the members of each set being separated by a slot 48, affording means for the insertion of the free end of a dividing strip.

55 The slots thus provided may be spaced along the circumference of the rosette in any desired number, so that floor panels of various shapes may be formed by running floor strips between rosettes at different angles.

60 In Figs. 10, 11, I illustrate still another type of insert, which may be used in spaced arrangement as shown in Fig. 5 with or without dividing strips, or which may be used in tile fashion in the manner illustrated in Fig. 4. Said insert is a square outline, being form-

ed by a square frame 49, the corners of which are joined by diagonal members 50, 51. The skeleton frame thus obtained is formed with an open top dovetailed chamber 52, adapted to receive and retain anti-slip material 53.

70 Like in the previous case, the outer portion of the frame is provided with a depending rib member 54, formed with laterally extending flange or lug sections 55, providing slots such as 56 at convenient places for the insertion of the ends of dividing strips which may be used to connect one unit to another. However, when these inserts are to be used in contiguous arrangement tile fashion as illustrated in Fig. 4, the lug or flange members will 80 naturally be omitted.

The actual application of one of these inserts in a floor is illustrated in Fig. 11 where 57 designates the floor foundation, 58 the foundation layer or bed, and 59 the finishing 85 layer of the floor. It will be observed that the flanges 55 rest directly on top of the surface of the foundation layer 58, thus effectively supporting the insert in position and causing the upper surface thereof to define 90 the depth at which the finishing layer of the floor must be laid.

It is obvious that although the drawings Figs. 6 to 11, illustrate frame members formed with open top chambers, adapted to 95 receive anti-slip material, it is quite possible to produce inserts intended for decorative purpose only, and for localizing cracks, having solid metal edges, showing through the surface of the floor, in a manner similar to that 100 of dividing strips of the ordinary type.

In so far as I know it is new to use inserts in terrazzo and similar floors, and especially inserts adapted to impart anti-slip properties to the floor. It will also be observed that 105 while the drawings show anti-slip units obtained by filling a chamber provided in the metallic head portion of a frame, as shown, this construction being comparable to the one described in connection with anti-slip 110 dividing strips, described and claimed in another application for patent, entitled, Methods of and means for producing anti-slip terrazzo floorings Serial No. 247,617, filed January 18, 1928, it is within the scope of 115 my invention to produce units or inserts in which the entire head is made of anti-slip material or of an ordinary floor aggregate composition pressed or formed about the upper part of a supporting metal frame; this construction being in its turn comparable to the one described and claimed by me in another application for patent, entitled Flooring strips, also filed simultaneously herewith.

120 My invention also extends to the use of anti-slip inserts of any description in connection with floors of the character specified, whether said anti-slip inserts include a metallic supporting frame or not. For instance, in the case of Fig. 1, the circular block 20' de- 125

limited by the inner circle of the annular structure may be made entirely of anti-slip material and may be used with or without the annular structure illustrated. Relatively 5 small inserts may be used for this purpose which need not necessarily be of a decorative nature, and the same may be used with or without the dividing strips, as the case may be.

10 From the foregoing it will be seen that my inventive idea may be carried into practice in a number of different ways and that the drawings will have to be understood as being intended for illustrative purposes only and 15 not in a limiting sense. I accordingly reserve myself the right to carry my invention into practice in all those ways and manners which may enter, fairly, into the scope of the appended claims.

20 I claim:

1. A unitary insert for terrazzo and similar floors, comprising an open metal frame having a rib member integral therewith formed in a predetermined design upwardly 25 projecting therefrom, said frame and rib member forming a latticed structure, adapted to be inserted through and to be retained by a body of floor composition, when in its plastic condition, and anchoring means there- 30 for integral with said frame.

2. A unitary insert for terrazzo and similar floors, comprising an open metal frame having a rib member integral therewith formed in a predetermined design upwardly 35 projecting therefrom, said frame and rib member forming a latticed structure, adapted to be inserted through and to be retained by a body of floor composition, when in its plastic condition, and anchoring means there- 40 for integral with and laterally projecting from said frame.

3. A unitary insert for terrazzo and similar floors, comprising an open metal frame having a rib member integral therewith formed in a predetermined design upwardly 45 projecting therefrom, said frame and rib member forming a latticed structure, adapted to be inserted through and to be retained by a body of floor composition, when in its plastic condition, and means integral with said 50 frame for connecting said frame to a floor dividing strip or strips.

4. A unitary insert for terrazzo and similar floors, comprising an open metal frame having a rib member integral therewith formed in a predetermined design upwardly projecting therefrom, said frame and rib member forming a latticed structure, adapted to be inserted through and to be retained by a body 55 of floor composition, when in its plastic condition, anchoring means therefor integral with said frame and means also integral with said frame for connecting said frame to a floor dividing strip or strips.

65 5. A unitary insert for terrazzo and simi-

lar floors, comprising an open metal frame having a rib member integral therewith formed in a predetermined design upwardly projecting therefrom, said frame and rib member forming a latticed structure, adapted 70 to be inserted through and to be retained by a body of floor composition, when in its plastic condition and means spaced along the periphery of said frame adapted to receive and retain the ends of floor dividing strips. 75

6. A unitary insert for terrazzo and similar floors, comprising an open metal frame having a rib member integral therewith formed in a predetermined design upwardly projecting therefrom, said frame and rib member forming a latticed structure, adapted 80 to be inserted through and to be retained by a body of floor composition, when in its plastic condition, said rib having a chamber and a filling for said chamber made of anti-slip 85 material.

7. A unitary insert for terrazzo and similar floors, comprising an open metal frame having a rib member integral therewith formed in a predetermined design upwardly 90 projecting therefrom, said frame and rib member forming a latticed structure, adapted to be inserted through and to be retained by a body of floor composition, when in its plastic condition, said rib member having an open 95 top chamber, and a body of material having a coefficient of friction higher than that out of which the device itself is made, inserted within said chamber.

8. A unitary insert for terrazzo and similar floors, comprising an open metal frame having a rib member integral therewith formed in a predetermined design upwardly projecting therefrom, said frame and rib member forming a latticed structure, adapted to be 100 inserted through and to be retained by a body of floor composition, when in its plastic condition, said rib member having an open top chamber, a body of material having a coefficient of friction higher than that out of which 105 the device itself is made, inserted within said chamber and anchoring means for said device integral with said frame.

9. A unitary insert for terrazzo and similar floors, comprising an open metal frame having a rib member integral therewith formed in a predetermined design upwardly 110 projecting therefrom, said frame and rib member forming a latticed structure, adapted to be inserted through and to be retained by a body of floor composition, when in its plastic condition, said rib member having an open top chamber, a body of material having a coefficient of friction higher than that out of which 115 the device itself is made, inserted within said chamber and anchoring means for said device integral with said frame.

10. A unitary insert for terrazzo and similar floors, comprising an open metal frame 120

- having a rib member integral therewith formed in a predetermined design upwardly projecting therefrom, said frame and rib member forming a latticed structure, adapted to be inserted through and to be retained by a body of floor composition, when in its plastic condition, said rib member having an open top chamber, a body of material having a coefficient of friction higher than that out of which the device itself is made, inserted within said chamber, anchoring means for said device integral with and laterally projecting from said frame, and means spaced along the periphery of said frame for receiving and retaining the end of floor dividing strips.
11. A terrazzo or similar floor, comprising a foundation bed and an upper layer of floor composition, and a plurality of unitary inserts inserted therethrough in a predetermined arrangement, said inserts each comprising an open metal frame having a rib member integral therewith formed in a predetermined design upwardly projecting therefrom, said rib member having its upper edge level with the surface of the floor, said frame and rib member forming a latticed structure, adapted to be surrounded by said floor composition, said frame having means for anchoring it to said foundation bed.
12. A terrazzo or similar floor, comprising a body of floor composition, a plurality of unitary inserts inserted therethrough in a predetermined arrangement, said inserts each comprising an open metal frame having a rib member formed in a predetermined design upwardly projecting therefrom, said rib member having its upper edge level with the surface of the floor, said frame and rib member forming a latticed structure, adapted to be surrounded by said floor composition, and a plurality of dividing strips inserted through said floor composition having their upper edges level with the surface of the floor cooperating with said inserts in producing an ornamental design for said floor.
13. A terrazzo or similar floor, comprising a body of floor composition, a plurality of unitary inserts inserted therethrough in a predetermined arrangement, said inserts each comprising an open metal frame having a rib member formed in a predetermined design upwardly projecting therefrom, said rib member having its upper edge level with the surface of the floor, said frame and rib member forming a latticed structure, adapted to be surrounded by said floor composition, and a body of anti-slip material carried by and following the outline of said rib member.
14. A terrazzo or similar floor, comprising a body of floor composition, a plurality of unitary inserts inserted therethrough in a predetermined arrangement, said inserts each comprising an open metal frame having a rib member formed in a predetermined design upwardly projecting therefrom, said rib member having its upper edge level with the surface of the floor, said frame and rib member forming a latticed structure, adapted to be surrounded by said floor composition, said rib member being formed with an open top chamber and a body of material having a coefficient of friction higher than that of the material out of which the device itself is made, inserted within said chamber.
15. A terrazzo or similar floor, comprising a body of floor composition, a plurality of unitary inserts inserted therethrough in a predetermined arrangement, said inserts each comprising an open metal frame and a rib member formed in a predetermined design upwardly projecting therefrom, said rib member having its upper edge level with the surface of the floor, said frame and rib member forming a latticed structure adapted to be surrounded by said floor composition, a body of anti-slip material carried by and following the outline of said rib member, and a plurality of floor dividing strips also inserted through said floor composition having their upper edges level with the surface of the floor, cooperating with said inserts in forming an ornamental design for said floor.

PASQUALE GALASSI.
